UNITED STATES PATENT OFFICE

CLESSIE L. CUMMINS, OF COLUMBUS, INDIANA. ASSIGNOR TO OIL ENGINE DEVELOPMENT COMPANY, OF COLUMBUS, INDIANA, A CORPORATION OF INDIANA.

OIL ENGINE.

Application filed July 30, 1924. Serial No. 729,143.

To all whom it may concern:

Be it known that I, CLESSIE L. CUMMINS, a citizen of the United States, residing at Columbus, in the county of Bartholomew and State of Indiana, have invented certain new and useful Improvements in Oil Engines, of which the following is a specification.

This invention relates to oil burning engines of the general type wherein the fuel is burned by the heat of the air compressed by the piston within the combustion chamber of the cylinder.

The principal object of my invention is to provide an oil burning engine which eliminates or overcomes many of the objections to, and defects in oil burning engines of those types in which the charge of oil is injected into the combustion chamber by a blast of compressed air delivered from an external source, as in the well-known Diesel engine, or in which the charge is injected into the combustion space by a preliminary explosion in an auxiliary chamber, as in the well known Hvid or Brons engines, or in which part or all of the fuel charge is ejected in liquid form directly into the combustion space by mechanical means, while at the same time my engine will possess many of the advantages of such types of engines and be more simple in design, more efficient and economical in operation, capable of developing high power, possessed of a marked degree of flexibility, and free from carbon troubles.

With the above and incidental objects in view, the invention consists in certain novel features of construction and combination of parts, the essential elements whereof are recited in the appended claims, and preferred and modified forms of embodiment of which are described in detail hereinafter and illustrated in full in the accompanying drawings, which form part of this specification.

Of said drawings, Fig. 1 is a vertical fragmentary section taken through the upper part of a four-cycle engine showing the preferred form of embodiment of my invention applied thereto; Fig. 2 is a bottom plan view of the inner cup-shaped member

of my injector; and Fig. 3 is a fragmentary section through an injector embodying a modified form of my invention.

Fig. 1 illustrates, in section, the upper part of a cylinder 6 and reciprocating piston 7 of a four-cycle engine, to which, for the purposes of illustration, I have shown the preferred form of embodiment of my invention applied. An air intake valve 8 and an exhaust valve 9 may be of any approved construction.

The fuel injector, in general, comprises a body member or plug 10, an injecting plunger 11, operable in the central bore 11' of the plug, a cup-shaped member 12 fitting over and about the lower end of the plug 10, a second cup-shaped member 13 of generally similar shape, fitted over the inner cup-shaped member 12, and a fuel inlet valve 14 mounted in a bore 15 in the plug. The lower end of the central bore in the plug is closed by the lower conical end of the cup 12 so that when the plunger 11 is retracted or elevated to the position illustrated in Fig. 1 an atomizing or vaporizing chamber 16 is formed under the plunger 11. The bottom of this chamber, formed by the cup 12, is conical and of the same contour as the lower conical end of the plunger 11, to form a seat for this conical end, and the apex of the conical seat is provided with a very shallow opening 17 into which the pointed end of the plunger 11 projects when the latter is in its lowered position. The lower or bottom face of the conical end of the cup 12, as best shown in Fig. 2, is provided with a centrally-located circular protruding portion 18 having grooves 19 therein radiating outwardly from the central opening 17, so that an annular oil space 20 around the portion 18 and conduits, formed by the grooves 19, are provided between the cups 12 and 13 when in assembled condition.

The lower end of the cup 13, which projects into the combustion chamber of the cylinder, is provided with very restricted passages or openings 21 communicating with the combustion chamber and radiating outwardly from the central opening 17.

The lower end of the fuel inlet valve

14 is pointed and is adapted to close the upper end of a conduit 22 leading to the annular space 20 and a large groove 20' in the bottom of the cup member 12.

5 I have not shown in detail in the drawings operating means for actuating the ejecting plunger 11 and the fuel valve 14, as any desired or approved form of devices may be used. The arms 26 and 27, shown 10 diagrammatically in dotted lines, may be considered as forming parts of the operating mechanisms for the plunger and valve respectively.

In the modified form of my invention, 15 shown in Fig. 3, the lower end of the plunger 11 has a concaved seat which may be spherical as shown, or conical, if desired. But one cup member 23 is employed and it is provided with a convex seat 24 which may 20 be spherical as shown, or conical if the lower end of the plunger 11 is provided with a concave conical end. The radiating distributing openings 21 open into the vaporizing chamber 16 adjacent the edge of the seat 24 and 25 are preferably arranged tangential to this seat. The fuel conduit 22 extends through the lower end of the cup member 23 and opens at the center of the seat 24 and upwardly into the vaporizing chamber 16.

30 The operation of the preferred form of my invention is as follows: During the suction stroke of the piston 7, air is drawn into the cylinder past the air inlet valve 8. During this same stroke, the fuel valve 14 is elevated by its operating mechanism to unseat its lower end and a charge of fuel, forced either by gravity or by a pump or other suitable means, flows through the oil conduit 22 into the annular chamber 20 and the 35 radiating passages 19. This flow of the charge forces the charge of oil already in such space and passages into the pointed end of the vaporizing chamber 16. This charge, which is deposited in the vaporizing chamber, has stood in the annular chamber 20 and the 40 passages 19 from the time it was deposited therein during the preceding suction stroke. Each charge of fuel, when it is deposited in the annular space 20 and the 45 grooves 19, serves to cool the pointed projecting end of the injector, and hence prevents it from getting so hot as to cause pre-ignition, or cause a deposit of carbon thereon, and at the same time the absorption of 50 the heat by the charge heats the oil and makes it more easily and thoroughly vaporizable. From the beginning of the period when the liquid charge is deposited in the lower end of the vaporizing chamber until 55 after the beginning but near the initial part of the compression stroke of the piston, I preferably slowly elevate the plunger 11 from its lowermost position to its retracted 60 position, shown in Fig. 1, so as to create a

partial vacuum in the vaporizing chamber 16 100 for the purpose of preventing the partial vacuum in the combustion chamber from causing any of the liquid fuel to drip or be drawn into the combustion chamber. I find that this is a very important feature. The 105 plunger 11 is then held in retracted position during the remainder of the compression stroke, and during such stroke part of the heated air, compressed in the combustion chamber and heated due to its compression, 110 is forced to flow through the openings 21 into the vaporizing chamber 16. These streams of highly compressed heated air rushing through the openings 21 sweep 115 through the heated oil in the lower end of the vaporizing chamber 16 with the result that the oil is entrained with the air and thoroughly mixed, atomized, and vaporized with it in the vaporizing chamber 16. Near the beginning of the power stroke of the piston, the plunger 11 is rapidly advanced or depressed until its lower end is firmly seated and during this movement of the plunger the dry gaseous mixture of fuel and air is rapidly forced out of the chamber 16 120 through the restricted radiating openings 21 into the combustion chamber of the cylinder. As this dry gaseous charge is injected into the combustion chamber it ignites or explodes, thereby greatly increasing the pressure in the combustion chamber, driving the 125 piston downwardly.

I find it is very important that the charge of liquid fuel be discharged into the injector at a point where it will be swept by and entrained with the compressed air entering the vaporizing chamber rather than be discharged at a point remote from the seat, else some or all of the fuel is not vaporized or equally distributed in the auxiliary chamber, with the result that some of it is injected into the combustion chamber in a liquid condition with accompanying deleterious results, such as extremely momentary high pressures, late combustion of part of the charge, decrease in power, deposit of carbon, and unequal distribution of the charge in the combustion chamber. When the plunger 11 is lowered, to inject the charge into the combustion chamber, the 130 plunger is fully advanced so that its lower end is seated against the seat to insure the injection of all of the dry gaseous charge from the vaporizing chamber in order that the maximum efficiency may be obtained and 135 the formation of carbon in the vaporizing chamber and the communicating restricted passages is prevented. I find that this is also an important desideratum of my invention, and with this in view the openings 21 are 140 preferably made as short and small as practical.

The operation of the modified form is sub-

stantially the same as that of the preferred form, described above. The compressed air, during the compression stroke rushes through the openings 21 and sweeps through 5 or over the oil deposited on or around the edge of the seat 24 with the result that the oil is thoroughly agitated and vaporized so that it forms with the heated air a dry gaseous mixture which is ejected in such form 10 into the combustion space when the plunger 11 is lowered.

I claim:

1. In an oil engine, the combination of a cylinder and a piston operable therein, a fuel vaporizing and injecting device comprising a chamber having restricted openings between it and the combustion space of the cylinder, a plunger operable in said chamber, means for discharging a charge of 20 liquid fuel directly into said chamber and at a point where it forms a pool over said openings so that the charge of fuel is heated, vaporized and mixed with the air forced from the combustion space into said chamber through said openings, and means for operating said plunger to eject the entire gasified mixture of air and fuel from said chamber through communicating openings into said combustion space.
2. In an oil engine, the combination of a cylinder and a piston operable therein, a fuel vaporizing and injecting device having its discharge end subjected to the heat of combustion in the combustion space of the cylinder and comprising a chamber having short restricted radiating openings between it and the combustion space of the cylinder serving as the sole means through which air enters said chamber, a plunger operable in 40 said chamber, means for conducting the liquid fuel through said heated end and discharging said liquid fuel into said chamber at a point directly in the path of air forced by said piston from the combustion space 45 through said openings so that the fuel is vaporized and mixed with such air in said chamber, and means for operating said plunger to eject the entire mixture of air and fuel from said chamber through said short openings into the combustion space.

3. In an oil engine, the combination of a cylinder and a piston operable therein, a fuel vaporizing and injecting device comprising a chamber having restricted communicating means between it and the combustion space of said cylinder, a plunger operable in said chamber, means for discharging liquid fuel into said device at a point which is in the path of the air forced 55 from said combustion space through said communicating means so that the fuel is mixed with and thoroughly vaporized by the air forced into said chamber, and means for retracting said plunger while the fuel is 60 being so deposited and subsequently advanc-

ing said plunger to eject the mixture of air and fuel from said chamber into said combustion space.

4. In an oil engine, the combination of a cylinder and a piston operable therein, a fuel vaporizing and injecting device comprising a chamber having restricted openings communicating with the combustion space of the cylinder, a plunger operable in said chamber, means for depositing fuel at 70 the discharge end of said chamber during the suction stroke of the engine, and means for retracting said plunger while the fuel is being so deposited and during the remainder of the suction stroke and then advancing the plunger to eject the mixture of fuel and air from said chamber into the combustion space.

5. In an oil engine, the combination of a cylinder and a piston operable therein, a fuel vaporizing and injecting device comprising a chamber having restricted communicating openings between it and the combustion space of the cylinder, a plunger operable in said chamber, means for depositing liquid fuel at the discharge end of said chamber during the suction stroke of the piston so that the air forced by the piston from the combustion space through said 80 openings mixes with and vaporizes the fuel 90 in said chamber, and means for retracting said plunger while the fuel is being so deposited and for advancing said plunger to eject the entire mixture of fuel and air from said chamber into the combustion space during the combustion stroke of the engine.

6. In an oil engine, the combination of a cylinder and a piston operable therein, a fuel vaporizing and injecting device comprising a chamber and a plunger operable in 105 said chamber which has a seat at its discharge end against which the end of the plunger seats when fully advanced, the device also being provided with fuel-feeding and restricted passages for causing the fuel to enter said chamber through said seat and the entire vaporized mixture of air and fuel to be ejected from said chamber through the restricted passages into the combustion space of the engine by the advance of said plunger 110 to said seat and means for retracting and advancing said plunger.

7. In an oil engine, the combination of a cylinder and a piston operable therein, a fuel vaporizing and injecting device comprising a chamber having a conical seat with a central opening at its discharge end and a plunger having a conical end to seat against said conical seat when the plunger is fully advanced, the device also being provided with fuel-feeding and restricted passages communicating with said opening for causing the fuel to enter said chamber through said opening and the vaporized mixture of air and fuel to be ejected from 120 125 130

said chamber through the restricted passages into the combustion space of the cylinder by the advance of said plunger to said seat, and means for retracting and advancing said plunger.

8. In an oil engine, the combination of a cylinder and a piston operable therein, a fuel vaporizing and injecting device having its inner end projecting into the combustion space of the cylinder so that it is subjected to the heat of combustion in the combustion space and also having a chamber with restricted communicating means between it and the combustion space, and oil feeding conduit means extending through said heated end for depositing a charge of oil at a point in the path of the air forced by said piston from the combustion space through said restricted communicating means, and a plunger operable to eject the vaporized mixture of air and fuel from said chamber into said combustion space.

9. In an oil engine, the combination of a cylinder and a piston operable therein, an injector having its discharge end subjected to the heat of combustion in the combustion space and provided with a vaporizing chamber, passage means in its discharge end to accommodate a charge of oil and conduct the charge of oil to said chamber, and restricted communicating means between said chamber and the combustion space; means for feeding a charge of oil to said passage means and thereby force the charge already therein into said chamber during the suction stroke of the piston, and a plunger for ejecting the vaporized mixture of air and fuel from said chamber into the combustion space through said communicating means.

10. In an oil engine, the combination of a cylinder and a piston operable therein, an injector having its discharge end subjected to the heat of combustion in the combustion space and provided with a vaporizing chamber, passage means in its discharge end to accommodate a charge of oil and conduct the charge of oil to said chamber, and restricted communicating means between said chamber and the combustion space; means for feeding a charge of oil to said passage means and thereby force the charge already therein into said chamber during the suction stroke of the piston, a plunger in said chamber and means for retracting said plunger while the charge of oil is being delivered into said chamber and for advancing said plunger during the compression stroke of the piston to eject the entire vaporized mixture of air and fuel from said chamber into the combustion space through said restricted communicating means.

11. The method of injecting a combustible charge of gasified oil and air into the combustion space of an internal combustion

engine, which consists in discharging a charge of oil into a vaporizing chamber at a point in the path of compressed air forced from the combustion space through restricted openings into said vaporizing chamber during the compression stroke of the engine so as to entrain and vaporize the charge of oil in such vaporizing chamber, and then mechanically ejecting the entire mixture of air and fuel from the chamber through said restricted openings into the combustion space.

12. The method of injecting a combustible charge of gasified oil and air into the combustion space of an internal combustion engine, which consists in discharging oil during the suction stroke into the vaporizing chamber at a point in the path of compressed air forced from the combustion space through short restricted openings into the vaporizing chamber during the compression stroke, retracting the plunger in said chamber during the suction stroke and then advancing the plunger to inject the entire combustible mixture of vaporized oil and air through said restricted openings into the combustion space during the combustion stroke of the engine.

13. The method of injecting a combustible charge into the combustion space of an internal combustion engine which consists in retracting the plunger in the vaporizing chamber during the suction stroke, delivering oil at the lower end of said chamber while the plunger is being retracted from its seat on the lower end of said chamber so that air forced through the short restricted communicating openings between the chamber and the combustion space during the compression stroke vaporizes the oil in said chamber, and finally advancing the plunger to its seat during the combustion stroke to eject the entire vaporized mixture of air and fuel from said chamber through said communicating openings into the combustion space.

14. The method of injecting a combustible charge into the combustion space of an internal combustion engine, which consists in depositing oil at the delivery end of the vaporizing chamber communicating with the combustion space through restricted openings, retracting the plunger in said chamber while the oil is being deposited and until the initial part of the compression stroke, and finally advancing said plunger by a rapid movement near the beginning of the combustion stroke of the engine to eject the entire vaporized mixture of air and fuel from said chamber into said combustion space through said communicating restricted openings.

15. The method of injecting a combustible charge of gasified oil and air into the combustion space of an internal combus-

tion engine, which consists in delivering one charge of oil to passage means, subjected to the heat of combustion, to discharge the pre-heated charge of oil already therein into the path of heated compressed air forced from the combustion space through restricted openings into a vaporizing chamber and finally ejecting the gasified mixture of oil and air from said chamber into said combustion space through said restricted openings by a plunger in said vaporizing chamber.

16. The method of injecting a combustible charge of gasified oil and air into the combustion space of an internal combustion engine, which consists in delivering one charge of oil to passage means, subjected to the heat of combustion, to discharge during the suction stroke of the engine the pre-heated charge of oil already therein into the discharge end of a vaporizing chamber where it is in the path of heated compressed air forced from the combustion space through restricted openings during the compression stroke of the piston, retracting the plunger in said chamber when the charge of oil is discharged into said chamber, and finally advancing said plunger to eject all

of the gasified mixture of oil and air from said chamber into said combustion space through said restricted openings during the 30 combustion stroke of the piston.

17. In an oil engine, the combination of a cylinder and a piston operable therein, a fuel vaporizing and injecting device having its discharge end subjected to the heat of compression and combustion in the combustion space of the cylinder and comprising a chamber having a seat at and restricted openings in said discharge end, a plunger operable in said chamber and adapted to 40 seat against said seat when the plunger is fully advanced, means for conducting a charge of liquid fuel through said heated end into the center of said seat to form a 45 pool over said restricted openings, so that the charge of fuel is mixed with the air forced from the combustion space into said chamber through said openings, means for retracting said plunger while the fuel is being deposited in said chamber and for advancing said plunger to said seat to eject the entire mixture of air and fuel from said chamber through said openings into said combustion space. 50

CLESSIE L. CUMMINS.
